UNITED STATES PATENT OFFICE.

NELS KROHN, OF CHICAGO, ILLINOIS, ASSIGNEE TO THE ADAMS & WESTLAKE COMPANY, OF CHICAGO, ILLINOIS, A CORPORATION OF ILLINOIS.

BRAKE-OPERATING MECHANISM.

1,175,645.

Specification of Letters Patent. Patented Mar. 14, 1916.

Application filed July 19, 1915. Serial No. 40,726.

To all whom it may concern:

Be it known that I, NELS KROHN, a citizen of the United States, and resident of Chicago, county of Cook, and State of Illinois, have invented certain new and useful Improvements in Brake-Operating Mechanism, of which the following is a specification, and which are illustrated in the accompanying drawings, forming a part thereof.

10 The invention relates to mechanism for operating the brakes of railway cars, and of the type in which a pawl is oscillatably mounted within a casing which swings about the axis of the brake staff, the pawl being

15 provided with a handle whereby it may be thrown into engagement with the coöperating ratchet on the staff by the brake-winding movement. A device of this kind is shown and broadly claimed in my co-pending application Serial No. 40,725.

The object of the present invention is to provide a simple and cheap, yet effective form of construction; and it consists of a structure such as is hereinafter described 25 and illustrated in the accompanying drawings, in which—

Figure 1 is a detail plan view of the device, with the cover plate of the ratchet and pawl-inclosing casing removed; Fig. 2 is a detail side elevation of the device; Fig. 3 is a detail section on the line 3—3 of Fig. 2; Fig. 4 is a bottom plan view of the ratchet and pawl-inclosing casing, showing the operating handle in section; and Fig. 5 is a detail of a wall of the casing and a portion of the pawl, showing a modified form of construction.

The usual brake staff is shown at 10, and as being journaled at its upper end in a wall 40 bracket 11, adapted to be attached to a part of a railway car. A holding ratchet 12 is fixed upon the staff adjacent the bracket, and a hand-operated pawl 13, pivoted to the bracket 11, coöperates with this ratchet. The 45 ratchet 12 is preferably provided with a sleeve 14, which extends upwardly through the bearing plate 15 which forms a part of the bracket 11, this sleeve constituting the journal for the staff. A ratchet wheel 16 fits upon the sleeve 14, and a pin 17, set through this wheel, the sleeve 14, and the staff 10, rigidly fixes these parts together. A casing 18 incloses the ratchet wheel 16, its bottom wall being apertured to receive 50 the sleeve 14 and turn freely thereon.

A pawl 19, mounted within the casing 18, coöperates with the ratchet wheel 16. This pawl is provided with a heel 20, having a bearing on the rear side wall of the casing 18. In the construction as shown in Fig. 1, 60 this heel is rounded and slides upon a complementary face formed on the wall of the casing. At its forward side the pawl 19 is provided with a toe 21, which is in sliding engagement with a curved face 22 formed on the adjacent side wall of the casing. This construction permits the pawl to rock on its heel, the toe serving to guide it in its oscillating movement.

An operating handle 23 is attached to the 70 pawl 19. A drop handle is shown, its attachment to the pawl being by means of a pivot pin 24. As the handle is moved forwardly in a direction to wind up the brake, its first action is to throw the nose of the pawl 19 75 into engagement with the teeth of the ratchet 16, further movement carrying the pawl, the casing, the ratchet wheel and the staff with it. When moved in the opposite direction the handle first rocks the pawl 80 backwardly on its heel, disengaging its nose from the ratchet wheel, the staff being held by the ratchet 12, and permitting the casing to swing back freely for a renewed engagement of the pawl with the ratchet. 85

A stop 25, formed on the bracket 11, limits the backward movement of the casing, and should a rigid handle be employed suitable means may be provided for holding it in its retracted position when not in service, 90 the pawl 19 being disengaged from the ratchet. When a drop handle is employed, as shown, provision is made for automatically holding the pawl out of engagement with the ratchet when the handle is lowered. 95 For this purpose the slot in the bottom 26 of the casing 18, which receives the handle when lowered, is formed with an inclined face 27, which acts upon the handle as a cam deflecting it to throw the pawl into the position indicated by dotted lines in Fig. 1. 100

As shown in Fig. 5, in place of the heel 20, as represented in Fig. 1, the heel of the pawl 19 may be a simple lug 28, fitting loosely within a pocket 29 in the side wall 105 of the casing.

I claim as my invention—

1. In a brake mechanism, in combination, a rotatable staff, a ratchet fixed on the staff, a casing oscillatable about the staff axis, a 110

pawl coöperating with the ratchet and having a rocking bearing on one wall of the casing and a sliding bearing on the opposite wall thereof, and a handle attached to the pawl.

2. In a brake mechanism, in combination, a rotatable staff, a ratchet fixed on the staff, a casing oscillatable about the staff axis, a pawl coöperating with the ratchet and having a rocking bearing on one wall of the

casing and a sliding bearing on the opposite wall thereof, and a handle pivotally attached to the pawl, the bottom wall of the casing having a recess to receive the handle when swung toward the staff, one wall of such recess being oblique to the radius of the casing whereby the handle is deflected laterally to disengage the pawl from the ratchet.

NELS KROHN.
